POST-OPERATIVE SLING FOR HAND OR ARM SURGERY CASES

Shirley B. Thompson, 5016 Williamsburg Blvd.,
Arlington, Va. 22207

Filed Mar. 7, 1974, Ser. No. 449,065

Term of patent 14 years

Int. Cl. D24—04

U.S. Cl. D83—1 J

FIG. 1 is a right side top perspective view from the front of my post-operative sling for hand or arm surgery cases, showing my new design;

FIG. 2 is a right side elevation view thereof;

FIG. 3 is a left side bottom perspective view from the rear thereof; and

FIG. 4 is a left side elevation view thereof.

I claim:

The new and ornamental design for a post-operative sling for hand or arm surgery cases, substantially as shown and described.
